INVENTOR.
André M. Mertzanoff
BY
Conrad A. Detrich
his ATTORNEY.

UNITED STATES PATENT OFFICE

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY

RADIATOR

Application filed April 30, 1929. Serial No. 359,334.

My invention relates to improvements in radiators, and the same has for its object more particularly to provide a simple and efficient construction which may be readily 5 adjusted and secured to desired position upon the floor.

Further, said invention has for its object to provide a radiator which is so constructed as to permit of the vertical riser and return being placed in close proximity to each other, and which while permitting of considerable longitudinal adjustment of the radiator in respect thereto will, nevertheless, be practically invisible.

Further, said invention has for its object to provide a radiator in which the water or steam spaces of the end sections, or group of end sections at each end of the radiator are of greater height than the intermediate sections, and the inner opposing sides of the projecting portions of said end sections or innermost of groups of end sections provided with pipe-receiving openings adapted for connection with a source of fluid heating 25 medium.

Further, said invention has for its object to provide a radiator construction in which all of the accessories, such as riser and connections, return valves, etc., will be disposed 30 wholly within the geometrical outlines of the radiator in order to permit of a relatively close-fitting, removable casing or enclosure being fitted therefrom.

Further, said invention has for its object to provide a radiator construction in which the riser and return connection are arranged inwardly of the ends of the radiator, and either below or above the intermediate portion thereof so that none of said parts shall project beyond the geometrical outline of the radiator as a whole.

Further, said invention has for its object to provide a radiator construction in which the water spaces of the end section shall be of greater height than the intermediate section in order that the riser and return connections and controlling devices may be disposed in such manner that the radiator will 50 present no projecting parts which might in-

terfere with a radiator casing or cover disposed thereover.

Further, said invention has for its object to provide a radiator construction in which the controlling valves are disposed below the 55 radiator and between the ends thereof, and the operating means for said valves carried upwardly so as to be accessible at or near the top of the radiator.

Other objects and advantages will in part 60 be obvious and in part be pointed out hereinafter.

To the attainment of the aforesaid objects and ends my invention consists in the novel features of construction, and in the combination, connection and arrangement of parts 65 thereafter more fully described and then pointed out in the claims.

In the accompanying drawing;

Figure 1 is a side elevation partly in section, showing one form of radiator constructed according to and embodying my said invention;

Fig. 2 is a vertical section taken on the line 2—2 of Fig. 1;

Fig. 3 is a front elevation showing a modified construction, and

Fig. 4 is a diagrammatic view showing several floors of the building with closely associated riser and return pipes, and a plurality 80 of radiators adjusted to different positions with respect to said supply pipe and return.

In said drawing 10 designates a radiator comprising a series of intermediate sections 11 which are here shown as of generally rectangular outline, and of uniform height, width and depth. Each of said intermediate sections is provided upon both sides adjacent to its upper and lower ends with suitable apertures to receive nipples 12 whereby the 85 sections may be communicatively connected.

The intermediate sections 11 are of uniform size, and the end sections 13 are taller than said intermediate sections and are connected thereto in such manner that said end 95 sections project both above and below the upper and lower edges of said intermediate sections and thus permit of the connection of a branch inlet pipe 17 to the inwardly-facing portions 14 of one end section, above the tops 100

of said intermediate sections, and of a return pipe 19 to the corresponding portion of the opposite end sections 13, below the bottoms of said intermediate sections.

5. Where possible the supply pipe 18 and return pipe 19 are preferably arranged closely together, and the radiator 10 so disposed that said pipes shall be at or near a point about midway between the ends of the radiator structure, as shown, for example, in the upper floor at Fig. 4.

The supply pipe 18 may be provided in its branch 17 with a suitable control valve 20.

The radiator including its connected parts 15 is preferably enclosed by a removable metallic cover or casing 26 which is provided at its base with suitable openings or recesses 27 for the admission of cold air, and at or near its top with suitable openings 28 for the discharge of the heated air. The top 26^a is preferably secured at its rear edge to the casing 26 by a hinge 29.

In order that the radiator may freely accommodate the casing 26, the end sections 13 are preferably made wider, or conversely, the intermediate sections 11 may be made narrower, in order to provide a space between the end sections and to the rear of the intermediate sections to permit of the inlet or 25 supply pipe 18 being carried downwardly or upwardly within the geometrical outline of the radiator. By this arrangement the radiator is freed of all projecting parts which would otherwise interfere with or prevent 30 the free application of the cover or casing to or upon the radiator. Further, each end section, instead of being single, as shown at Figs. 1 and 2, may consist of a plurality or 35 group of sections as shown at Fig. 3. The construction of the end sections, in providing 40 projecting portions both above and below said intermediate sections, renders this form of radiator suitable for use in connection with two pipe or hot water systems.

45 At Fig. 3, is shown a construction similar to that shown at Figs. 1 and 2, comprising intermediate sections 11^a, and end sections 13^a, 13^b, each of which latter is composed of a series or group of larger sections, instead of 50 a single section as shown at Figs. 1 and 2.

The diagrammatic view, Fig. 4, shows a number of radiators supplied by the same closely-associated supply pipe and return pipe which may be adjusted laterally at different floors of a building to suit windows or other structural conditions, or to meet decorative requirements. The supply pipe 18 and return 19 being connected adjacent the lower ends of the end section 11.

60 It will be noted that by making the intermediate sections 11 of smaller outline than the end sections 13, and assembling the sections, as illustrated, vertical and transverse marginal spaces are provided between the 65 outer edges of the intermediate sections and

the outer edges of the end sections, of which marginal spaces any one or more will readily accommodate the necessary supply pipe, return pipe and valves, and that the same will lie entirely within the geometrical outlines of the radiator as a whole.

70 From the foregoing it will be apparent that all the radiator operating parts and connections are disposed entirely within the geometrical outlines of the radiator structure, and as a result will permit of enclosing the radiator in a comparatively smaller or closer fitting removable casing 26 than would be possible if any pipes, valves or other parts or accessories were connected or secured to the radiator and caused to project beyond its geometrical outline or contour.

75 Having thus described my said invention, what I claim and desire to secure by Letters Patent is:

80 1. A radiator comprising a plurality of intermediate sections and end sections communicatively connected, the end sections next adjoining said intermediate sections being of greater height than said intermediate sections and extending below the same and provided upon their inwardly opposing sides with pipe-receiving apertures, substantially as specified.

85 2. A radiator comprising a plurality of intermediate sections and end sections communicatively connected by apertures adjacent to their upper and lower ends; said last-named apertures being arranged horizontally 90 in alignment, said intermediate sections being shorter than said end sections whereby to provide extended surfaces on said end sections projecting vertically beyond said intermediate sections, and the inner opposing sides of the extended portions of said end sections provided with pipe-receiving apertures disposed below said lower line of apertures, substantially as specified.

95 3. A radiator comprising a plurality of intermediate sections, and end sections; said intermediate sections being communicatively connected together and to said end sections at their upper ends, and communicatively connected together at their lower ends, and to said end sections at points above their lower ends, and pipe-receiving apertures upon the inwardly opposing sides of said end sections arranged at points below the point where the lower ends of said intermediate sections are secured together, substantially as specified.

100 Signed at the city of New York, in the county and State of New York, this 26th day of March, one thousand nine hundred and twenty-nine.
